UNITED STATES PATENT OFFICE.

KUNT OLSAN MJOLSNES, OF NASHWAUK, MINNESOTA.

CENTRIFUGAL PUMP.

1,365,006.

Specification of Letters Patent. Patented Jan. 11, 1921.

Application filed November 19, 1919. Serial No. 339,213.

To all whom it may concern:

Be it known that I, KUNT O. MJOLSNES, a citizen of the United States, and a resident of Nashwauk, in the county of Itasca and State of Minnesota, have invented certain new and useful Improvements in Centrifugal Pumps, of which the following is a specification.

My invention is an improvement in centrifugal pumps, and the invention has for its object to provide mechanism in connection with pumps of the character specified, for permitting the pump to be repaired when it becomes worn, without requiring extensive operations on the pump, merely by removing the worn portion and substituting a new portion.

In the drawings:

Figure 1 is a top plan view of the casing with the upper half removed,

Fig. 2 is an enlarged detail of the upper end of Fig. 1,

Fig. 3 is a section on the line 3—3 of Fig. 1,

Fig. 4 is a side view, with parts broken away.

In the present embodiment of the invention, the impeller 1 is secured to a shaft 2, which is journaled in bearings in the casing or housing, consisting of the upper section 3^a and the lower section 3. The casing or housing has an annular passage at the periphery of the impeller, the said passage gradually increasing in diameter from the intake end 4 thereof to the outlet end 5 thereof.

Thrust rings 7 are arranged on the hub 6 of the impeller on each side of the same, and the water driven by the pump is taken in through the hubs and discharged by the impeller vanes into annular passage 4—5 to its final discharge. As is known, the edge of the annular passage becomes worn, after a time depending upon the nature of the liquid handled by the pump, and the liquid instead of taking the proper course, will eddy about the pump center. To prevent this, I place resistance plates 8 within the housing to conform to the curves and lines of annular passage 4, the impeller, etc.

These plates which are arranged on the opposite sides of the impeller have their inner ends and sides shaped to fit the contour

of the hub, thrust rings, and impeller surfaces, as clearly shown in Fig. 1. Their outer ends are shaped to conform to the contour of annular passage "4," and their outer edges are straight. These plates are arranged in rabbets 9 in the housing 3, so that their upper faces are flush with the upper face of the housing section, and they are held in place by screws 10 which are countersunk in the plates to be flush with the upper face thereof.

As shown more clearly in Fig. 2, the plates at their outer ends and at their inner edges have lugs 11 which extend toward each other, at the peripheral surface of the impeller. These plates are formed from flat sheet steel, and will vary in shape to conform to the design of various pumps. They prevent wear, being of resistant material and when worn, they may be easily removed and replaced by new plates. In practice, the plates need be not more than $\frac{1}{16}$ to $\frac{1}{4}$ of an inch in thickness.

In the improved pump the water is drawn in through the inlet 12 to the axis of the impeller and is forced outwardly by the rotation of the impeller to the annular passage 80 of the casing 3—3^a. The rotation of the impeller and the force of the water coming from behind drives the water around the annular passage and out at the outlet 13. When the casing 3—3^a becomes worn the liquid, instead of filling the annular passage to the outlet 13, will merely eddy, or turn around the impeller hub. The plates remedy this, for they prevent eddies and churning of the liquid. The purpose of the lugs 90 11 is to more clearly define the annular passage and the impeller chamber. The plates 8 act in the same manner as deflectors, constraining the liquid to flow outwardly substantially radial to the casing 3—3^a to the 95 annular passage.

I claim:—

In a centrifugal pump, the combination with the housing having the impeller chamber and the annular passage outside of the 100 impeller chamber and communicating therewith, the impeller in the chamber and the shaft to which it is secured journaled in the housing, of resistance plates arranged adjacent to the intake end of the annular passage, said plates being arranged on opposite

sides of the impeller chamber and being extended in from the walls thereof toward the impeller and having their inner edges shaped to fit closely up to the sides of the impeller, each plate having a lug extending inwardly toward the opposite plate at the

peripheral surface of the impeller and partially separating and defining the annular passage from the impeller chamber, said plates being detachable for the purpose 10 specified.

KUNT OLSAN MJOLSNES.
